Claims priority, application Luxembourg
June 19, 1948

2 Claims. (Cl. 89—33)

1

The present invention relates to semi-automatic firearms the reloading of which takes place automatically but with which the gunner must operate the trigger upon every shot, automatic firearms firing by bursts and arms capable of working either in a semi-automatic or in a fully automatic manner, these firearms including a movable breech piece having a reciprocating motion in a direction substantially parallel to that of the firing axis of the arm. It is more particularly concerned with arms of this kind supplied with ammunition from a flexible belt on which the cartridges are disposed at regular intervals of a value hereinafter called the "pitch" of the belt, said belt being actuated by a feeding device operated by the movable breechblock of the arm in such manner that the forward movement of the belt takes place by successive steps equal to fractions of the pitch and in particular to one half thereof.

According to a feature of my invention, in a firearm provided, for the discontinuous drive of the cartridge belt by a feeding device operated step by step by the movable breechblock so that two successive steps correspond to a total feed displacement of an amplitude equal to the pitch and take place, respectively, the first one during the recoil stroke of said breechblock and the second one at the end of the frontward return stroke thereof, I arrange a camming mechanism through which said feeding device is operated by the movable breechblock, in such manner that the first step begins only after said breechblock has moved through a substantial portion of its recoil stroke, whereby, in particular, I reduce the path of travel during which the nose of the breech piece rubs along the lower generatrix of the cartridge brought along the axis of the arm by the first step.

Preferred embodiments of the present invention will be hereinafter described with reference to the accompanying drawings, given merely by way of example and in which:

Figs. 1 to 4 show, respectively in vertical section, in top view with parts in section and parts cut away, and in cross sections in two different respective vertical planes, an automatic firearm made according to the invention;

Fig. 5 diagrammatically shows, in four different operating positions, certain parts of the feed device included in the arm shown by Figs. 1 to 4;

Fig. 6 is a transverse half-section of a first construction of the device operated by the movable breechblock for actuating the feeding device;

2

Figs. 7 and 8 show, respectively in cross section and in longitudinal section on the line VIII—VIII of Fig. 7, a second construction.

In the following description, it will be supposed that the invention is applied to a machine-gun, fed with cartridges by means of a belt 1 on which are fixed cartridges 2, the forward movement of the belt taking place in a discontinuous manner, by successive steps equal each 10 to one half of the pitch, under the action of a feeding device.

This firearm includes, in the usual manner, a barrel (not shown on the drawings) connected at the rear with a breech casing 3 in which moves, 15 against the action of a recuperator spring 4, a movable breechblock 5 provided, at its upper front end, with a nose 5a capable of introducing into the barrel cartridge chamber, during the return stroke of the breechblock, the cartridge 20 brought along the axis of said chamber by the belt feeding mechanism (feeding device), which is to be more explicitly described hereinafter.

The whole of the barrel and of breech casing 3 is supported by a stock 6 with respect to which 25 said whole is given a reciprocating motion (recoil movement and return movement) during the operation of the firearm.

I mount on said stock a cover 7, intended to receive the feeding device, and a feed guide 8, the latter supporting the belt 1 and being provided 30 with a gap in its middle portion to permit passage, between two introduction edges 8a, of the breechblock nose 5a during the step of introduction of the cartridge into the arm barrel.

It should be noted here that cover 7 does not 35 participate in the recoil movement of breech casing 3 and that, due to the fact that it is stationary, it is particularly adapted to act as support for the feeding device intended to move belt 1.

40 This feeding device is arranged to produce a discontinuous step by step movement of said belt, the movement of one cartridge over a distance equal to the pitch therefore taking place in two steps, to wit a preparatory step of an amplitude 45 equal to one half-pitch, the effect of which is to bring this cartridge into a waiting position (shown for cartridge 2 in the Diagram I of Fig. 5), and a complementary step, also of one half-pitch, ensuring the passage of said cartridge from this waiting position to the introductory position (shown at 2 on the Diagram III of Fig. 5).

For a predetermined cartridge, the preparatory step and the complementary step above referred 50 to overlap two successive full reciprocations.

(backward and forward strokes of breechblock 5), every full reciprocation of said breechblock producing first the complementary step relative to the cartridge which is in waiting position and the introduction of this cartridge into the cartridge chamber and, then, the preparatory step relative to the next cartridge which is thus brought into waiting position.

The cycle of operation of the feeding device having thus been defined in a general manner, according to the main feature of my invention, said device is controlled by breechblock 5 in such manner that the complementary step of a cartridge in waiting position takes place during the breech recoil stroke and begins only after said breechblock has travelled through a substantial portion of this recoil stroke.

In this way, and contrary to what took place with the already known feeding device of the same kind, for which the complementary step took place immediately upon the beginning of the breechblock recoil stroke, I avoid rubbing of the nose 5a of said breechblock over the whole length of the lower generatrix of the cartridge fed into position of introduction, between the edges 8a of passageway 8, by said supplementary step.

In particular, if cartridge 2 is brought into introductory position only after the nose 5a of the breechblock has moved past the rear of the neck 2a of the cartridge case, any risk of deteriorating this relatively weak portion of said cartridge case is avoided.

For instance, in the case of cartridges of the usual type, the beginning of the complementary step may correspond to breechblock 5 having already moved a distance equal to two thirds of its recoil stroke.

It seems particularly advantageous to make the feeding device according to the embodiment illustrated by the drawings.

Such a device includes two sliding members 9 and 10 carried by cover 7 and capable of moving transversely with respect to the axis of the firearm, these sliding members being fitted with respective pawls 11 and 12, said pawls being each retracted against the action of a spring (not shown) when the corresponding sliding member moves in a direction opposed to the direction of feed of belt 1 and coming on the contrary to catch a cartridge and to drive said belt over a distance corresponding to one half of the pitch when said sliding member is moved in the direction of forward feed of the belt.

Sliding members 9 and 10 are controlled by an oscillating lever 13 hinged about a pivot axis 14 on cover 7, and connected to said sliding members in such manner that they move in opposite directions to each other, for which purpose, for instance, sliding member 10 is directly acted upon by the front end of lever 13 and there is interposed between said end and sliding member 9 a link 15 pivotally mounted on cover 7 about an axis 16 located substantially opposite the middle point of said link.

Oscillating lever 13 is driven by movable breechblock 5 by means of a camming mechanism including a cam 17 pivoted (about axis 18) to breech casing 3 and subjected to the action of a return spring 19 intended to keep said cam in correct position when said cover is closed. Connection between cam 17 and lever 13 takes place through a device adapted to permit recoil movement of breechblock casing 3 with respect to cover 7, for instance through the intermediate

of a roller 20 carried by said lever 13 and moving between guides 21 rigid with cam 17.

A cam follower constituted by a roller 22 is mounted on breechblock 5 opposite cam 17, the active portions of said cam being arranged in such fashion that, on the one hand, the complementary step of a cartridge in waiting position takes place after the breechblock has moved a distance corresponding to a substantial portion of its recoil stroke (active portion 17a) and, on the other hand, the preparatory step corresponding to the next cartridge takes place at the end of forward return of said breechblock (active portion 17b).

The whole of the active portions 17a (corresponding to the end of the recoil stroke of the breechblock) and 17b (corresponding to the second fraction of its return stroke) therefore has a characteristic curve with a double concavity which is shown by a reinforced line on the diagrams of Fig. 5, points r_a and r_b of this curve (which might possibly coincide together) corresponding respectively to the beginning of the intervention of active portion 17a during the recoil stroke of movable breechblock 5 and of active portion 17b during the return stroke of said movable breechblock.

I will now indicate in a more detailed manner and with reference to the diagrams of Fig. 5, the various phases of operation of the feeding device above described.

Considering the firearm just when a cartridge previously introduced into the cartridge chamber is fired (Diagram I, the next cartridge 2 is in waiting position and roller 22 in contact with the front end of the active portion 17b of cam 17. During the first fraction of the recoil stroke of the breechblock and up to the time when roller 22 moves past point r_a , the position of cam 17 remains unchanged since said roller remains practically away from said active portion 17b; the nose 5a of the breechblock therefore moves freely toward the rear between the edges 8a of passageway 8. On the contrary, from this time on, roller 22 attacks the active portion 17a and causes cam 17 to swing (positions at the beginning of this attack and position at the end of the recoil stroke represented respectively by Diagrams II and III). This phase corresponds to the complementary step which brings cartridge 2 between the edges 8a, i. e. across the path of travel of the nose 5a of the breechblock; during the first portion of the return stroke of the breechblock 5, cartridge 2 is extracted from the belt which is stationary and is introduced into the cartridge chamber; when roller 22 moves past point r_b and only from this time on, the active portion 17b is acted upon and cam 17 is returned (position shown by Diagram IV) into the position it occupied initially (Diagram I), this phase of the operation corresponding to the preparatory step for the next cartridge, which cartridge is then brought into waiting position at a distance from the firing axis equal to one half of the pitch. The various elements of the arm are then back into their initial position and the cycle is repeated upon the next recoil stroke of the breechblock.

With such an arrangement, the recoil movement of the breechblock is braked only for a relatively short time, due to the fact that the cartridge is brought relatively late into introductory position.

Furthermore, as already stated, this arrange-

ment practically eliminates any risk of deterioration of the cartridges by the breechblock nose.

Finally, I avoid any risk of wedging of the breechblock by the feeding device if, for any accidental cause, said breechblock has moved backward to a distance non negligible but however insufficient for catching the cartridge, in which case, for an arm fitted with a feeding device of a conventional type which starts bringing the cartridge into position of introduction as soon as the recoil stroke begins, wedging of the arm would be unavoidable.

Advantageously, at least a portion of breechblock 5 is protected against the transverse reaction, produced for instance by the action of roller 22 against cam 11, by fitting this breechblock with at least one bearing piece, such for instance, as a roller 23, cooperating in the transverse direction with a bearing surface, such for instance, as a rectilinear rail 24 rigid with the breech casing 3.

Preferably, roller 23 is so located as to absorb the perturbing reaction in the very region where it originates, whereby I avoid any tilting torque which might produce wedging of the breechblock.

For this purpose, I may for instance, as shown by Figs. 1 to 3, mount roller 23 coaxially with roller 22 and immediately below (or above) it.

I may also, as shown by Fig. 6, provide two rollers 23 located coaxially with roller 22, respectively above and below said roller, in which case the perturbing torque is wholly eliminated.

According to a modification which also permits of eliminating the perturbing torque, I place rollers 22 and 23 side by side (in the transverse direction) as shown by Figs. 7 and 8.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. A firearm of the type described in which the cartridges are detachably carried by a belt and juxtaposed along said belt transversely thereto at a constant interval or pitch from one another, which firearm comprises, in combination, a stock, means forming a cartridge chamber movable with respect to said stock in a direction parallel to the axis of said chamber, a cover rigid with said stock, a breech casing rigid with said chamber, a breechblock movable in said breech casing with a reciprocating motion parallel to the axis of said cartridge chamber and including a recoil stroke and a return stroke, means carried by said breechblock for pushing into said cartridge chamber, during the return stroke of said breechblock, a cartridge located in a given position parallel to said axis, a feeding device for moving said belt transversely to said axis with a step by step displacement of an amplitude equal for every step to one half of said pitch, a lever pivoted to said cover and operatively connected with said feeding mechanism for operation thereof, a cam pivoted to said breech casing operative-

ly connected with said lever, and a roller carried by said breechblock in cooperating contact with said cam for actuating it, said cam being shaped to cause every step of the displacement of said belt that brings one cartridge into said given position to occur only after said breechblock has moved through a substantial part of its recoil stroke and to cause the next step of this belt displacement to take place at the end of the next return stroke of said breechblock.

2. A firearm of the type described in which the cartridges are detachably carried by a belt and juxtaposed along said belt transversely thereto at a constant interval or pitch from one another, which firearm comprises, a combination, a stock, means forming a cartridge chamber movable with respect to said stock in a direction parallel to the axis of said chamber, a cover rigid with said stock, a breech casing rigid with said chamber, a breech block movable in said breech casing with a reciprocating motion parallel to the axis of said cartridge chamber and including a recoil stroke and a return stroke, means carried by said breech block for pushing into said cartridge chamber, during the return stroke of said breech block, a cartridge located in a given position parallel to said axis, a feeding device for moving said belt transversely to said axis with a step by step displacement of an amplitude equal for one step to a portion of said pitch and for the next step to another portion of said pitch such that the sum of these two portions is equal to said pitch, a lever pivoted to said cover and operatively connected with said feeding mechanism for operation thereof, a cam operatively connected with said lever and pivoted intermediate its ends to one of the breech mechanism elements constituted by said breech casing and said breech block respectively, a cam follower carried by the other of said elements to travel in a substantially straight path, said cam having cam surfaces on each side of said pivot and shaped to be engaged by said cam follower at areas spaced from the pivot to actuate the cam to cause every step of the displacement of said belt that brings one cartridge into said given position to occur only after said breech block has moved through a substantial part of its recoil stroke and to cause the next step of this belt displacement to take place at the end of the next return stroke of said breech block.
